Primary Examiner—Gary D. Watson*Assistant Examiner*—Susan Bennett Hattan*(74) Attorney, Agent, or Firm*—Peter L. Olson(57) **CLAIM**

The ornamental design for end cap for a package with flexible walls, as shown and described.

DESCRIPTION

FIG. 1 is a perspective front view of end cap showing the new design. As shown, the end cap is oriented to face front;

FIG. 2 is a plan view of the front side of the end cap;

FIG. 3 is a plan view of the back side of the end cap;

FIG. 4 is a side elevational view of the end cap (the view from the other side is identical);

FIG. 5 is an elevational view of the top of the end cap (as viewed from above FIG. 1) thereof; and,

FIG. 6 is an elevational view of the bottom of the end cap (as viewed from below FIG. 1) thereof.

The broken lines in the drawings are shown for illustrative purposes only and form no part of the claimed design. In addition, the surface shading illustrated in the drawings is provided merely to highlight the contour of design; it is not intended to be illustrative of texture or gloss.
